ROTARY-GRAVE BURNER

Weston M. Fulton and Sidney R. Galyon, Knoxville, Tenn., assignors to W. J. Savage Company, Inc., Knoxville, Tenn., a corporation of Tennessee

Application July 27, 1944, Serial No. 546,770

4 Claims. (Cl. 110—35)

1

This invention relates to an improvement in rotary-grate burners, of the character set forth in the co-pending application of Weston M. Fulton, on Burners for solid fuels, Serial No. 546,771, filed July 27, 1944.

In the above-mentioned application, and also in an earlier application of Weston M. Fulton, Serial No. 535,848, filed May 16, 1944, a fire-clay baffle was used in the upper part of a rotary burner to furnish a hot surface against which the gaseous products of combustion impinge upon rising from the fire bed. Where such a fire-clay baffle is used in association with rotary grate-bars of the type set forth in the above-mentioned application of Weston M. Fulton, for Burners for solid fuels, Serial No. 546,771, such a fire-clay baffle would not effectively support the grates during a portion of their travel in the upper region of their orbit and would also have a tendency to heat the grates, whereas it is desirable that they be cooled as much as possible.

The object of this invention is to improve the character of the baffle used in a rotary-grate burner to enable it to be water-cooled, whereby such a baffle may support the grates during this portion of their travel while also cooling them in this region. Such a water-cooled baffle is interposed between the grates in their upper region and the fire bed in the burner so as to insulate the grates from the heating effect of the fire bed at this upper region, thereby tending to cool the grates.

The invention is shown as applied to a rotary-grate burner in the accompanying drawings, in which:

Fig. 1 is a side elevation of the burner;

Fig. 2 is a vertical cross-section therethrough; and

Fig. 3 is a longitudinal section therethrough on the line 3—3 of Fig. 2.

In the form of the invention illustrated in the drawings, the burner comprises two main parts designated respectively at 1 and 2, each of which is constructed substantially of annular form and mounted in stationary position against rotation. The parts 1 and 2, being elongated horizontally, form an enclosed hollow non-rotating shell extending about the rotating grates mounted therein.

The burner part 1 is formed with an outer wall

3 (see Figs. 2 and 3), an inner wall 4 and end walls 5 and 6, enclosing therebetween an annular space or water chamber 7. This annular space 7 is adapted to be filled with water or other cooling medium which may be supplied thereto by convectional circulation from the boiler to which the burner is attached in a manner similar to that described in the prior application on Fuel burners for boilers, Serial No. 529,502, filed April 4, 1944, as hereinafter referred to more in detail.

In a similar manner, the part 2 has an outer wall 8, an inner wall 9, and end walls 10 and 11, enclosing an annular space 12 which is adapted to be filled with water in the same manner and 15 from the same source as described above in connection with the burner part 1.

The burner parts 1 and 2 are formed with air chambers 18 and 22 in the lower portions thereof, which are open to the peripheries of these burner 20 parts through slots 20 and 24, respectively.

Mounted on one side and near the bottom of the burner, as shown in Fig. 1, is a wind-box 25 which extends throughout the major portion of the length of the burner, including the parts 1 25 and 2, enclosing therein the slots 20 and 24, as will be evident from Figs. 1 and 3. The wind-box 25 is adapted to supply air to these slots, as indicated by the arrows in Figs. 2 and 3. An air duct 26 extends to the wind-box 25 from a blower 27 30 for supplying air, as needed, to the wind-box, which in turn directs it into the burner, as described.

At the interior of the burner part 1 is a series of grate-bars 28, each of which is formed slightly 35 arcuate in cross-section, as shown in Fig. 2, and has beveled opposite edges 29. The opposite ends of the grate-bars 28 are loosely interconnected with driving rings 31 and 32 (Fig. 3), each of which is notched at its inner edge to receive an 40 end of the grate-bar therebetween. The driving rings 31 and 32 are mounted to rotate freely within opposite ends of the burner part 1, and move the grate-bars through an orbit substantially in contact with the inner wall 4 throughout 45 the major portion of the circumference of the burner part 1, but with the grate-bars slightly spaced from each other leaving longitudinal slots or openings 36 therebetween, as shown in Fig. 2.

Each of the driving rings 31, 32 has ratchet 50 teeth 37 on its peripheral portion thereof, in the

illustrated embodiment of the invention, as means of rotating the rings and grate-bars.

The burner part 2 is provided also with a driving ring 39, which is similar to the rings 31 and 32, except that it extends continuously throughout the width of the burner part 2 and has an inwardly disposed annular rim 40 at the inner end of the burner. Furthermore, the driving ring 39 has ratchet teeth 41 on its peripheral rim portion, but of shorter pitch than the ratchet teeth 37 so as to provide for finer stepping adjustment of the driving ring 39, than of the driving rings 31, 32.

The driving ring 39 has elongated openings or slots therein, loosely receiving grate-bars 43 which are sufficiently loose in the openings to permit inward movement of the grate-bars and also to allow spaces therearound for the passage of air from the chamber 22 into the interior of the burner to support combustion.

At the fuel inlet end of the burner is a stationary burner head 45 (Fig. 3), which forms an enclosure for the cylindrical burner structure. The burner head 45 is hollow to provide a water space 46 therein, and having inlet and outlet water connections at its bottom and top respectively, each of which is provided with a push nipple, one being shown at 48 at the top, as a means of connecting the burner head with the burner part 1. These connections permit free circulation of water between the water chamber 46 in the burner head and the water chambers 7 and 12 in the burner parts 1 and 2 in a manner usually employed in the construction of cast iron boilers.

One end of the cylindrical burner is supported by means of the burner head 45, which is carried by legs 49 on a base 50, preferably bolted thereto. The opposite end of the burner may be supported in any convenient manner, but we prefer that it be seated in a fire-brick wall 51 (Fig. 1) which connects the outlet end of the burner with a heating boiler 52. The fire-brick wall 51 has a chamber 53 therein, receiving the products of combustion from the burner and having a fire-brick face in opposed relation to the open end of the burner.

When the burner parts 1 and 2 are assembled together with the burner head 45, they constitute an integral non-rotating enclosure for the rotating grates. One end of this enclosure is connected with the furnace structure including the fire-brick wall on which the enclosure is mounted. Hence, it is only necessary to support separately the opposite end of the structure.

The burner head 45 is provided also with the fuel inlet 54 opening into the inner side of the burner at a point preferably located at the vertical longitudinal plane through the axis of the burner, and preferably above the axis. This fuel inlet is preferably in the form of a zigzag conduit through which the fuel may be directed into the outer end of the burner from a suitable source of fuel supply, such as a hopper.

Referring to Fig. 1, the rotor of the blower 27 is keyed on the armature shaft of an electric motor which is mounted on the base 50, and which motor is connected also through a V-belt 59 with a pulley 60, which is keyed to the drive shaft 61 of a speed reducer 62 that is mounted on the base 50 adjacent the motor.

The speed reducer 62 has a reduced speed power output shaft on which is mounted a crank 64 for turning movement thereby. A link-arm 65 has one end pivoted to the crank 64 and its opposite end pivotally connected with the lower

end of a swinging lever-arm 66. The lower end of the lever-arm 66 is bifurcated to receive therein in the adjacent end of the link-arm 65. The lever-arm extends upwardly at the end of the burner and has its upper end pivotally mounted on a support 67 on the burner head 45 for lateral swinging movement in response to the operation of the motor acting on the lever-arm through the link 65.

The lever-arm 66 is also bifurcated at its middle portion, as shown at 73 in Fig. 1, thereby providing an open space in which is located a walking beam 74, pivoted at 75 intermediate its ends to the lever-arm 66. The opposite ends of the walking beam member 74, carry links 76 and 77 pivoted thereto. These links 76 and 77 extend transversely of the burner head 45 in opposite directions, and have their outer ends pivotally connected (Fig. 2) at 78, 79, respectively, with crank-arms 80, 81, keyed to shafts 82, 83 journaled to turn freely in bearings 84, 85, respectively, integral with the burner part 1. Also keyed to the shafts 82, 83 are short crank-arms 86, 87, two crank-arms being provided on each shaft, which crank-arms carry pawls 88, 89, held in engagement with the teeth 37 of the driving rings 31, 32 by means of springs. On the outer ends of the shafts 82, 83, are keyed crank-arms 92, which carry pawls 94, held in operating engagement with the teeth 41 of the driving ring 39 by means of springs. Crank-arms 92 are shorter than the crank-arms 86, 87, so as to provide for smaller throw of the pawls 94, than of the pawls 88, 89, consistent with the smaller size of the teeth 41 than the teeth 37.

The foregoing structure is set forth more in detail, and claimed, in the co-pending application of Weston M. Fulton, on Burners for solid fuels, Serial No. 546,771.

One or more inlet connections are provided at 103 in the stationary burner grate enclosure, and similar outlet connections 104, leading respectively to the bottom and top portions of the steam or hot water boiler 52. Thus water from the bottom of the boiler will be directed into the water passages of the burner enclosure through the connection 103 where it will be heated and returned to the boiler through the top connection 104.

Referring to Fig. 3, the burner head 45 has integral therewith, a hollow member 105 which is in open communication with the chamber 46 of the burner head so that water can circulate freely therebetween. The member 105 extends throughout the entire length of the interior of the burner, as shown in Fig. 3, and is crescent-shaped in cross-section, as shown in Fig. 2. This member 105 is spaced from the interior wall 4 of the grate enclosure to permit the grates 28 and 43 to slide freely through the space between the wall 4 and the member 105. The member 105 preferably is not concentric with the wall 4 of the grate enclosure, the eccentricity being sufficient to make the space between the two increase somewhat as the grates pass around in the direction of the arrow in Fig. 2.

The member 105 has integral with its terminal edges, two channels 106 extending lengthwise thereof, and have channels 107 at opposite ends thereof, in which channels 106, 107 rests the edges of a fire-clay baffle 108. The purpose of this baffle is similar to that described in the co-pending application of Weston M. Fulton, Serial No. 535,848, filed May 16, 1944, for Burners for solid fuels. The baffle 108 is preferably spaced some-

what from the member 105, as indicated at 109 to reduce the heat exchange therebetween.

In the operation of the burner, the motor drives the blower 27 and also the operating parts described above, which rotate the driving rings 31, 32, and 39. As the driving rings thus rotate in the direction indicated by the arrow in Fig. 2, they carry with them the grate-bars 28 and 43, along with the burning fuel that lies on the grate-bars, at least within the fuel bed indicated at B in Fig. 2. The grate-bars are loosely supported and are so connected with the driving rings that the driving force applied to the bars tends to push them outward from the axis of rotation to bear against the inner wall 4 of the water-cooled enclosure. They are thus maintained in firm contact with this cooled surface while they are passing through the region covered by the major portion of the fuel bed B in the lower segment of the burner, which is the region in which they are subjected to the most intense heat.

As the grate-bars 28 are carried forward in the direction indicated by the arrows, they enter the spaced between the water-cooled member 105 and the outer enclosure. As the bars approach the region vertically above the center of rotation, they are free to drop down by gravity onto the peripheral surface of the member 105. Here it will be noted that the action of gravity gradually shifts the grate-bars away from the water-cooled enclosure towards the member 105. Also the bars are relieved of the weight of fuel as they rise above the fuel bed, and hence the driving force is reduced to a minimum, and correspondingly reducing the component of force tending to deflect the grate-bars outwardly. Consequently, the bars, upon entering the space between the member 105 and the water-cooled enclosure, soon drop by their own weight down onto the periphery of the member 105 and bear thereon in their movement over the upper portion of said member. These bars are then carried around on this member to where they emerge from the space mentioned, and in so doing, reach a region where the bars bear outwardly against the enclosure wall 4.

It will be noted that the construction and arrangement of the grate-bars and their driving mechanism, as described, cause these grate-bars to be held in contact with the surrounding cooling surface by yielding forces, i. e., gravity and mechanical power transmitted through two slidably connected surfaces.

Since the curvature of the member 105 is eccentric to that of the enclosure wall, the space therebetween increases from the point where the grates enter this space to the point where they leave it. The object of this arrangement is to prevent any possibility of the grates becoming clogged by any foreign matter which may accidentally exist in the fuel, and which may adhere to the bars and be carried by them into this space. It will be evident from Fig. 2 that any particles small enough to be carried by the grates through the restricted entrance to this passage, would be carried progressively along to constantly increased freedom of movement so that it could not clog the grates.

The increased size of this grate passage from its entrance to its exit also permits the grates to change their relative relationships moving in a non-circular orbit, and thus free the air spaces 36 between them from small pieces of fuel which may drop therein. It is evident that as each forward moving grate-bar drops down onto the

member 105, the space between it and the next adjacent grate-bar, is enlarged somewhat, thus freeing all particles contained in this space. Furthermore, as the grate-bars move to the exit side of this space, they again change relationships, and finally their relationship is changed for a third time as they move into and through the fuel bed B, as shown in Fig. 2. This constant shifting action makes the grate-bars self-cleaning and has proven from practical tests of the construction to possess great merit.

As fuel is fed into the burner at the fuel inlet 54, it drops onto the grates or lower edge portion of the fuel bed and is carried around by the grate-bars through the fuel bed. It is there supplied with air from the wind-box 25 through the slots 20 and air chambers 18, thence through the openings or slots 36 between the grates into the bed of burning fuel, as indicated by the arrows in Figs. 2 and 3.

The fire-clay baffle 108 is similar to the corresponding baffle set forth and claimed in the application, Serial No. 535,848, being used for a similar purpose. Here the baffle has an additional advantage, however, of protecting the grates from the burning fuel. The water-cooled member 105 affords added protection for the grates and also furnishes a relatively cool surface for them to rest upon while moving through the upper portion of their path of rotation. While either of these members 105 or 108 may be used alone without the other, in some installations, especially where other means are available to prevent pre-cooling of the gaseous products of combustion, we prefer to use both baffles for general purposes.

We claim:

1. A burner for solid fuel comprising a structure including rotary grates mounted for movement through an orbit and adapted to support a fuel bed in the lower portion of said orbit, and a water-cooled baffle extending beneath the grates at the upper region of the orbit and on the opposite side of the orbit from the fuel bed, being transversely curved and having a peripheral surface supporting the grates thereon during movement through the upper portion of the orbit.

2. A burner for solid fuel comprising a structure including rotary grates mounted for movement through an orbit and adapted to support a fuel bed in the lower portion of said orbit, and a water-cooled baffle extending beneath the grates at the upper region of the orbit and positioned between the upper portion of said grates and the lower fuel-supporting portion of said grates, being transversely curved and having a peripheral surface supporting the grates thereon during movement through the upper portion of the orbit, and power means for moving the grates through the orbit and having loose connection with the grates permitting relative transverse movement thereof.

3. A burner for solid fuel including rotary grates mounted for movement through an orbit and adapted to support a fuel bed in the lower portion of said orbit, and a fluid-cooled baffle extending beneath the grates at the upper region of the orbit and on the opposite side of the orbit from the fuel bed, said baffle having a surface supporting the grates thereon during movement through the upper portion of the orbit.

4. A burner for solid fuel comprising a structure including rotary grates mounted for movement through an orbit and adapted to support

a fuel bed in the lower portion of said orbit, and a fluid-cooled baffle extending beneath the grates at the upper region of the orbit and positioned between the upper portion of said grates and the lower fuel-supporting portion of said 5 grates, said baffle having a surface supporting the grates during movement through the upper portion of the orbit, and power means for moving the grates through the orbit.
